UNITED STATES PATENT OFFICE.

SAMUEL B. GOLD, OF INDEPENDENCE, MISSOURI, ASSIGNOR TO WEBER ENGINE COMPANY, OF KANSAS CITY, MISSOURI, A CORPORATION OF IOWA.

INTERNAL-COMBUSTION ENGINE.

Application filed October 8, 1923. Serial No. 667,219.

This invention relates to internal combustion engines, and more especially to engines of the two-cycle crank-case compression type. 5
In the oil fields, in particular, it is very desirable that an engine be extremely flexible, that is be capable of an almost instantaneous increase or decrease in speed and power in response to corresponding changes 10 in the volume of fuel supplied; and shall be easy to start, as in developed oil fields one man only is usually available for starting purposes. It is also desirable that the possibility of loss of control and the consequent 15 racing of the engine, and the chance of injury from back firing, shall be avoided, and that efficient water circulation be maintained.

The object of the invention therefore is 20 to produce a two-cycle crank-case compression engine possessing the features of advantage enumerated as desirable, and in addition, features of construction guarding against danger from backfiring, and against 25 loss of control by the operator, and features providing for an efficient and continuous circulation of water for cooling purposes. A further object is to generally improve engines of the class outlined.

With these objects in view, the invention 30 will now be described by reference to the accompanying drawing illustrating one form of construction which has been devised for embodying the proposed improvements, 35 after which those features deemed to be novel will be particularly set forth and claimed.

In the drawing—

Figure 1 is a side elevation of an internal 40 combustion engine embodying the invention.

Figure 2 is a vertical enlarged detail section taken on the line II—II of Figure 1.

Figure 3 is an enlarged section taken on 45 the line III—III of Figure 1.

Figure 4 is a front elevation of the engine, and in operative relation thereto, a water tank and connections between said tank and the engine, embodying the invention.

Figure 5 is an enlarged cross section of 50 the engine in the vertical plane of the connection therewith of the water circulating and stimulating pipeways disclosed by Figure 4.

Figure 6 is a horizontal section taken on 55 the line VI—VI of Figure 4.

Referring now to the drawings, 1 indicates a two-cycle crank-case compression engine of conventional type, in which the water-jacket chamber 2 (Figure 5) is connected to a water tank 3 by pipe-ways 4 and 5, the pipe-way 4, through which water passes to the chamber 2, being equipped with the customary check valve 6 to prevent back flow from the chamber.

The customary gas supply pipe 7, leads to a chamber 8 surmounted by a governor 9, driven by a belt and pulley connection 10, or the like, from the shaft 11 of the engine.

The governor stem 12 actuated as usual by variations of speed of the governor, extends into chamber 8, and has any suitable valve 13 controlling the port 14 in communication with a gas chamber or reservoir 15. A hollow skeleton cage 16 is screwed or otherwise secured in the wall of the engine and establishes communication, at times, between the gas reservoir 15 and the crank-case of the engine. A valve 17 is adapted for engagement with the inner end of the cage, and a spring 18, applies force tending to hold the valve seated, the arrangement being such that only suctional force produced in the crank-case shall be available to unseat the valve for the charging of the crank-case with gas, which in the normal operation of the engine, is supplied to the reservoir through the governor-controlled port 14.

It is frequently desirable, especially in 90 the oil fields, to instantly increase the speed and power of an engine, and to as quickly reduce the speed to normal when the work requiring greater speed or power has been accomplished. The most satisfactory method

of instantly increasing the supply of fuel is by means of a by-pass, and heretofore the by-pass pipes have been controlled by globe valves operated by long cables from points more or less remote from the valves. This method is dangerous, because slippage or breakage of the cable on an attempt to close the valve, results in loss of control of the gas intake with the consequent racing of the engine and possibility of wreckage of the engine and danger incident thereto.

To obviate the chance of losing control of the engine, the by-pass pipe 19 of this inven-

tion, is provided with a casing 20 having a valve-seat 21 for engagement by a valve 22 held normally closed or seated by a spring 23, and the stem 24 of the valve is connected 5 to a pull-cable 25 leading to a more or less remote point convenient to the operator, who can therefore, instantly unseat the valve when the necessity for augmenting the supply of gas to the reservoir arises. In the 10 event the cable breaks, no loss of control is entailed, as the spring instantly reseats the valve and thus closes the by-pass and restores control to the governor.

The air supply to the crank-case is through 15 a breather 26, not detailed, or by any other conventional air-intake, which admits air when the piston 27 creates a vacuum or partial vacuum in the crank-case by moving toward the head or combustion chamber end 20 of the cylinder, this vacuous condition also unseating valve 17, as hereinbefore suggested, for the admission of gas from the reservoir to the crank-case.

The piston in its advance toward the head 25 of the cylinder, closes the transfer port as customary, and compresses the charge of mixed gas and air transferred through the previous power stroke of the piston from the crank-case to the cylinder, and the piston 30 in such travel recharges the crank-case with gas and air by suctional action as explained. As the compressed charge is ignited the piston is driven back toward the crank-case and compresses the explosive mixture therein. 35 In such travel, the transfer port is uncovered and the explosive mixture passes therethrough to the combustion chamber of the cylinder and in the customary manner, aids in the scavenging of the dead or exhaust 40 gases through the exhaust port.

In two-cycle engines having crank-case compression, it is essential for efficiency of operation, that both the fuel and air ports shall be susceptible of adjustment, to accommodate variance of vacuum or suction, and hence provide for a mixture giving perfect combustion. The conventional breather mentioned makes provision for adjustment, as far as the air is concerned, and the 45 spring 18 can be tensioned to give the requisite fuel control by valve 17, especially when such valve is employed in conjunction with the reservoir 15, which, in the event of the creation of a vacuous condition in the 50 crank-case chamber demanding momentarily a larger supply of gas than the supply pipe is capable of delivering, is prepared to instantly supply the full charge needed and thus insure a proper mixture under such 55 conditions.

To provide for efficient water circulation, at all times, power developed by the engine is utilized to produce a water injection effect on the water in pipe 4, and in carrying this 60 into effect, the cylinder is provided with a

port 28 connected by a pipe-way 29 to pipe-way 4, the pipe-way 29 having a check-valve 30 adapted to open only under power impulses originating in the combustion chamber, so that water standing in the pipe-way 70 cannot enter the cylinder, which might occur if the valve was dispensed with. It is obvious of course, that if the top of the pipe-way was disposed at a lower level than the water-level in the tank, a check valve 75 or its equivalent would be indispensable as water would enter the cylinder at the end of each power stroke of the piston. In this connection it is to be understood that a part of the energy of each explosion enters the 80 port 28 and causes water in pipe-way 29 to squirt with an injecting effect into the water-jacket chamber and this stimulates circulation from the tank by way of pipe-way 4 into the water-jacket chamber and 85 from said chamber and pipe-way 5 into the tank, and it is to be noticed that these impulses stimulating water circulation are set up just prior to the completion of the power 90 stroke of the piston as the port 28 is so located that it is not uncovered by the piston until the power stroke of the latter is nearly ended, so that the power utilized is practically waste power and hence does not appreciably affect the efficiency of the engine operation. 95

For the above description it will be apparent that the invention embodies the features of advantage set forth as desirable and that it is susceptible of modification in various details without departure from the principle of construction or mode of operation involved. 100

I claim:

1. In an internal combustion engine, the 105 combination of an intake gas valve adapted to be opened by a vacuous condition in the engine crank-case and means to seat such valve when such vacuous condition ends, a gas line leading to the said valve, a governor-actuated valve controlling the gas line, a by-pass from the gas line to said intake valve, 110 and an automatically-closing valve controlling the by-pass.

2. In an internal combustion engine, the 115 combination of a gas reservoir for communication with the crank-case, a valve to be unseated by a vacuous condition in the crank-case, and establish communication between the latter and the reservoir, means to reseat 120 the valve when such vacuous condition ends, a gas line connected to the reservoir, a governor-controlled valve in the gas line, a by-pass from the gas line to said reservoir, and an automatically-closing valve controlling 125 the by-pass.

3. In an internal combustion engine, the combination of an intake gas valve adapted to be opened by a vacuous condition in the engine crank-case and means to seat such 130

valve when such vacuous condition ends, a gas line leading to the said valve, a governor-actuated valve controlling the gas line, a by-pass from the gas line to said valve, a yieldingly-seated valve normally closing the by-pass, and manually-operable means for unseating the by-pass valve.

5. In an internal combustion engine, the combination of a gas reservoir for communication with the crank-case, a valve to be unseated by a vacuous condition in the crank-case, and establish communication between the latter and the reservoir, means to reseat the valve when such vacuous condition 10 ends, a gas line connected to the reservoir, a governor-controlled valve in the gas line, a by-pass from the gas line to said reservoir, a yieldingly-seated valve normally closing the by-pass, and manually-operable means 15 for unseating the by-pass valve.

6. In an internal combustion engine of the crank-case compression type, having a port in the crank-case wall, the combination of a reciprocating piston for creating a vacuous 20

condition in the crank-case, in its compression stroke, a gas reservoir exterior to the compression chamber and in communication with said port, a valve closing said port and adapted to be opened as the piston makes its compression stroke and sets up a vacuous 25 condition in the crank-case, means to close said valve as the vacuous condition of the crank-case ends, a gas line leading to said reservoir, a governor-actuated valve controlling the gas line, a by-pass from the gas line 30 to the reservoir, an automatically-closing valve in the by-pass, and manually-operable means to unseat the by-pass valve.

7. In an internal combustion engine, the combination of an intake valve, a gas line 40 leading to said valve, a governor operated valve controlling said gas line, a by-pass leading from said gas line to said intake valve, and a valve controlling said by-pass.

In witness whereof I hereunto affix my 45 signature.

SAMUEL B. GOLD.
